(57) CLAIM

The ornamental design for a cosmetic box, as shown and described.

DESCRIPTION

FIG. 1 is a perspective view of a first embodiment of a cosmetic box showing the new design, the cosmetic box shown in a closed state;

FIG. 2 is a perspective view of the cosmetic box of FIG. 1 shown in an open state;

FIG. 3 is a top view thereof;

FIG. 4 is a bottom view thereof;

FIG. 5 is a side view thereof;

FIG. 6 is another side view thereof;

FIG. 7 is a top view thereof; and

FIG. 8 is a bottom view thereof;

FIG. 9 is a perspective view of a second embodiment of a cosmetic box showing the new design, the cosmetic box shown in a closed state;

FIG. 10 is a perspective view of the cosmetic box of FIG. 9 shown in an open state;

FIG. 11 is a top view thereof;

FIG. 12 is a bottom view thereof;

FIG. 13 is a side view thereof;

FIG. 14 is another side view thereof;

FIG. 15 is a top view thereof; and,

FIG. 16 is a bottom view thereof.

The broken lines illustrate a portion of the cosmetic box and form no part of the claimed design.
